Primary Examiner — Samantha Wood

(57) **CLAIM**

The ornamental design for a watch, as shown and described.

DESCRIPTION

1. Watch
- 1.1 : Front View
- 1.2 : Rear View
- 1.3 : Top View
- 1.4 : Bottom View
- 1.5 : Left Side View
- 1.6 : Right Side View
- 1.7 : Front Perspective View
- 1.8 : Rear Perspective View

1 Claim, 8 Drawing Sheets

CERTIFICATE OF CORRECTION

PATENT NO. : D1,006,646 S
APPLICATION NO. : 35/514123
DATED : December 5, 2023
INVENTOR(S) : Taye Berhanu

Page 1 of 10

It is certified that error appears in the above-identified patent and that said Letters Patent is hereby corrected as shown below:

On the Title Page

Delete the title page and substitute therefore with the attached title page consisting of the corrected illustrative figure.

In the Drawings

Please replace the drawings issued in the above patent with the drawings 1.1 – 1.8 attached.

Signed and Sealed this
Fifteenth Day of July, 2025

Coke Morgan Stewart
Acting Director of the United States Patent and Trademark Office
